US0D1094351S

(12) **United States Design Patent** (10) **Patent No.:** **US D1,094,351 S**
(45) **Date of Patent:** **** Sep. 23, 2025**

(54) **CASE FOR ELECTRONIC DEVICE**

(71) Applicant: **Samsung Electronics Co., Ltd.**, Suwon-si (KR)

(72) Inventors: **Yoonyoung Kim**, Suwon-si (KR); **Jinie Ryu**, Suwon-si (KR); **Bumsoo Park**, Suwon-si (KR)

(73) Assignee: **SAMSUNG ELECTRONICS CO., LTD.**, Gyeonggi-Do (KR)

(**) Term: **15 Years**

(21) Appl. No.: **29/950,387**

(22) Filed: **Jul. 2, 2024**

(30) **Foreign Application Priority Data**

Jan. 10, 2024 (KR) 30-2024-0001323

(51) **LOC (15) Cl.** **14-03**

(52) **U.S. Cl.**

USPC **D14/250**

(57) **CLAIM**

The ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an exploded top view thereof showing the two components of the case for electronic device separated for clarity of disclosure.

The bracket in FIG. 9 to show the relationship or order of assembly of various parts of the case for electronic device forms no part of the claimed design.

The broken lines in the figures depict portions of a case for electronic device that form no part of the claimed design.

1 Claim, 7 Drawing Sheets
